(57) **CLAIM**

The ornamental design for a bow string release component, as shown and described.

DESCRIPTION

FIG. 1 is a front elevational view.

FIG. 2 is a top elevational view.

FIG. 3 is a bottom elevational view; and,

FIG. 4 is a rear elevational view.

The broken line showing, in FIGS. 1 and 4, is for illustrative purposes only and forms no part of the claimed design.
